FREDERIC E. KIP, OF MONTCLAIR, NEW JERSEY.

WEFT-CONTROLLING MECHANISM FOR LOOMS.

SPECIFICATION forming part of Letters Patent No. 743,292, dated November 3, 1903.

Application filed February 17, 1903. Serial No. 143,766. (No model.)

To all whom it may concern:

Be it known that I, FREDERIC E. KIP, a citizen of the United States, and a resident of Montclair, New Jersey, have invented certain new and useful Improvements in Weft-Controlling Mechanisms for Looms, of which the following is a specification.

This invention relates to mechanism designed to control the stoppage of the loom or to set in operation a weft-replenishing mechanism when the weft or filling in the running shuttle is exhausted to a predetermined extent.

The invention is adapted especially to double-shuttle looms, and is designed to effect the operation of either the stopping mechanism or the weft-replenishing mechanism upon the occurrence of the above-indicated emergency in either shuttle.

In the following specification I have described a mechanical feeler or detector device which when actuated operates through the usual knock-off mechanism; but it is to be understood that the invention may be applied to a double-shuttle loom either to stop the loom when required or through the usual mechanisms to automatically control the time of operation of the weft-replenishing mechanism.

Another part of the invention resides in an electrical indicating device controlled by the detector to announce to the attendant weaver that the filling in one or both of the shuttles has been exhausted.

In the accompanying drawings, Figure 1 is a plan of a portion of a loom, showing the application of the present invention, certain parts being in section and certain other parts being shown diagrammatically. Fig. 2 is a section on the plane of the line 2 2 of Fig. 1. Fig. 3 is a section on the plane of the line 3 3 of Fig. 1. Fig. 4 is view, partly in section and partly in elevation, showing the position of certain parts when the filling on one of the filling-holders is exhausted. Fig. 5 is a detailed perspective view of a part of the controlling mechanism illustrated in the previous figures. Figs. 6 and 7 are views corresponding to Figs. 3 and 4, respectively, and show a modified form of construction. Fig. 8 is a view, partly in central section, and Fig. 9 is a cross section on the line 9 9 of Fig. 8,

of a form of bobbin that may be employed in connection with the feeler. Fig. 10 is a view, partly in section, and Fig. 11 is a cross-section on the line 11 11 of Fig. 10, of another form of bobbin that may be employed. Fig. 12 is a side view of the bobbin shown in Fig. 8. Figs. 13 and 14 are sectional detail views of controlling devices having adjusting means thereon.

Similar numerals indicate similar parts in the several views.

In the present specification for the purpose of illustration I have utilized certain forms of controller-feelers described in my applications Serial No. 107,409, filed May 15, 1902, Patent No. 724,113, March 31, 1903, and Serial No. 108,454, filed May 22, 1902, Patent No. 724,114, March 31, 1903, both for weft-controlling mechanisms.

Referring to the drawings, the numeral 10 designates the breast-beam of the loom; 11, the lay; 12, the knock-offlever; 13, the shipper-lever; 14, the weft-fork; 15, the weft-fork slide 75 engaging the knock-off lever; 16, the weft-hammer, and 17 the shuttle-box on the lay. All of these parts are well known and require no detailed description. It may be said, however, that when the vibrating weft-hammer engages the slotted arm 18 of the rocking weft-fork the slide 15 is moved toward the front of the loom, and by rocking the knock-off lever sets free the shipper-lever, thereby stopping the loom.

In order to accomplish the object of the present invention I have devised several means, two of which I have illustrated. In that form shown in Figs. 1 to 5 a rock-shaft 32, mounted in suitable supports 33, has at 90 one end a crank 35, which engages a slotted arm 36, pivotally mounted or hinged at 39 on the weft-fork slide 15. When the shaft 32 is rocked, the crank 35 depresses the free end of the arm 36 into the path of the vibrating weft-hammer 16, and this has the effect to move the weft-fork slide 15 and stop the loom through the medium of the knock-off and shipper levers.

In double-shuttle looms it is obvious that 100 the shaft 32 should be rocked upon the exhaustion of the filling in either the upper or lower shuttles. This is accomplished by providing a feeler for both the upper and lower

shuttles and causing the feelers to act through a common connection upon the shaft 32. The feelers are alike in construction and comprise casings 19, secured to a bracket 20 on the breast-beam. In the casings 19 are mounted the feelers 21, which may be rods having sliding bearings in said casings. Within the casings are springs 22, which abut at one end against the front end of the 10 casing and at the other against collars 23 or the like on the feelers. These springs tend to press the feelers out or toward the lay. On the outer end of each feeler is a suitable head 24 and at the other end there may be 15 lock-nuts 25 or the like to limit the movement. Pivotaly mounted in a slot in each feeler or its head at 30 is a lever-trip 31, the shorter arm or heel 40 of which preferably depends below the feeler.

20 When the lay beats up and the shuttles are properly boxed at this side of the loom, each feeler enters its box at an aperture 26 therein and also enters the shuttle at a coincident aperture 27 therein. The weft or filling 28 on the bobbin 29 in the shuttle impinges on the head of the feeler and drives the latter forward or into its casing.

The heel 40 is so disposed that so long as there is a sufficient quantity of filling in both 30 shuttles said heels are held out of contact with the shuttles or equivalent impinging means and no movement is imparted to the shaft 32; but when the filling is exhausted to a predetermined extent in either shuttle 35 the feeler of that shuttle enters to a greater extent than before and permits the heel 40 to be impinged upon by the side of the shuttle, thus throwing up the lever 31 of that particular feeler.

40 In order that the shaft 32 may be rocked when the filling in either shuttle is exhausted to a predetermined extent, an arm 41 is secured by suitable means to said shaft 32, and said arm has at its outer end a bearing 45 42 for a rod 43, said rod being secured in its bearing by a set-screw or other suitable means. Supported on the rod 43 are arms 34 and 44, the former extending over in close proximity to or bearing upon the lever 31 on the upper 50 feeler and the latter extending over in close proximity to or bearing upon the lever 31 on the lower feeler. The arms 34 and 44 may be suitably adjusted along the rod 43 by means of set-screws or other means. So long 55 as the heels 40 of the levers 31 are held out of contact with their respective shuttles no motion will be imparted to the shaft 32. When, however, the filling in either one of the shuttles is exhausted to a predetermined extent, 60 as illustrated in the upper shuttle in Fig. 4, the heel 40 of lever 31 of the upper feeler is impinged upon by the side of the shuttle, thereby raising the long arm of said lever and with it the arm 34. The effect of such 65 movement is to rock shaft 32.

If the exhaustion occurs in the lower shuttle, the arm 44 is raised in a similar manner

as that above described, with the same effect upon the shaft 32. When said shaft is thus rocked by the movement of either the arm 34 70 or the arm 44, the crank 35 depresses the free end of arm 36 into the path of the vibrating weft-hammer 16, thus moving the weft-fork slide 15 and knock-off lever 12 and stopping the loom through the medium of 75 the shipper-lever.

A spring 45, secured to the lower end of rod 43 and to a fixed part of the loom, serves to retain the arms 34 and 44 in their normal 80 positions.

The weft or filling exhaustion indicating mechanism above described comprises, in effect, two independently-operable divisions, one adapted to coöperate with the upper shuttle and the other with the lower shuttle, both 85 of said divisions being connected through a single means to the rock-shaft 32, such connection, as shown, being a bell-crank lever carrying suitable contact-arms 34 and 44.

In Figs. 6 and 7 I have shown a modified 90 form of controller-feeler adapted to double-shuttle looms, such form utilizing some of the features of my Patent No. 724,113. This modification comprises a carriage 60, slidably mounted in a guide on a bracket forming a 95 prolongation of the breast-beam. A yielding pusher 53, backed by a spring 54, is mounted to slide longitudinally in the carriage 60. An arm 55 on the pusher 53 projects through a slot 56 in one arm of a lever 57, fulcrumed 100 in bearings on the carriage 60, whereby if the arm 55 is in engagement with the lever 57 when the pusher is driven in by impingement against the side of the shuttle through aperture 26 said pusher will carry the carriage 105 with it. To prevent this taking place at each alternate beat up of the lay and to permit it to occur at predetermined times, a tripping-feeler 58 is employed. This is backed by a 110 relatively light spring 59 and is mounted slidably in the pusher 53 and carries a collar 62, which plays in a slot in the pusher and is adapted to engage the shorter arm of the lever 57. The head of feeler 58 is adapted to enter an aperture 27 in the side of the shuttle when the lay beats up and is impinged upon by the filling 28, the feeler being thus driven into the pusher. This occurs during the normal operation of the loom, and as the proportions are such that the feeler 58 is first 115 impinged upon and driven in before the pusher 53 is struck by the shuttle it follows that the collar 62, acting on the shorter arm of the lever 57, throws said lever out of the path of the arm 55 on the pusher before the 120 latter is moved. When the filling shall have become exhausted to a predetermined extent, the shuttle will impinge upon the pusher and move it into engagement with the lever 57, the effect being to move the carriage 60.

130 As shown in Figs. 6 and 7, the controller-feeler comprises two divisions, one coöperating with the upper shuttle and the other with the lower shuttle. The parts of the divisions

are similar, so that the description above given applies to both. To adapt this form of controller to double-shuttle looms, I provide a rod 63, having a suitable bearing, if necessary, and suitably connected to set for operation the loom-controlling mechanism. The rod 63 carries a cross head or bar 62', adapted to engage lugs 61 on both the upper and lower carriages 60. It is obvious that when either carriage 60 is moved upon exhaustion of the filling, as indicated in Fig. 7, the impingement of the lug 61 against the cross-head 62' will impart a longitudinal movement to the connecting-rod 63, thus setting for operation the loom-controlling mechanism.

In all of the forms of devices herein illustrated there will be always a predetermined amount of surplus filling or initial winding of filling remaining on the bobbin or filling-holder at the time of actuation of the weft-controlling device. In Fig. 1 this surplus is shown situated on the barrel of the bobbin at the point 64, where the feeler strikes, said barrel being recessed at that point. In Figs. 8, 10, and 12 this surplus filling may be advantageously situated in a groove 65 at the end of the bobbin or filling-holder, said bobbin having an aperture 66 extending entirely through the barrel at the steps, as shown in Figs. 8 and 9, or recessed at 67 at diametrically opposite sides, as shown in Figs. 10 and 11. A bobbin so provided with recesses or with an aperture permits the feeler to enter the shuttle to a considerable extent at the next beat up of the lay after the filling has been removed from over the mouth of the recess or aperture. Thus the impingement of the shuttle against the actuating parts of the detector-feelers may be delayed until the filling is wholly exhausted from the body of the bobbin, leaving unused only the amount of surplus in the groove 65. In fact, it is possible with either form of bobbin shown to exhaust the filling down to the surplus in the groove 65. For shuttles other than self-threaders—that is, those in which the bobbin is knocked in, owing to various conditions of weaving and character of the thread—it may be desirable to locate the recess or aperture in the barrel at the steps. For certain classes of weaving it is especially advantageous to have the aperture extending completely through the bobbin or to recess the bobbin upon two diametrically opposite sides for the reason that the barrel of the bobbin is often out of alignment due to warping. If there is a recess upon one side only, the delivery end of the bobbin or filling-holder in such case would not lie central in the shuttle, and the filling would therefore break in paying off. By having an aperture extending entirely through the bobbin or having a recess on both sides the bobbin or filling-holder if out of alignment may be turned so as to bring it into alignment.

Where the loom may be stopped from any one of a number of causes, it is important that

the weaver should know at once where to look for the cause of the stoppage. In Fig. 1 I have illustrated an indicating device operated through a connection with the mechanical feeler to indicate that the filling has become exhausted. The indicating device may be any one of a number of like annunciators 46, 47, and 48, each comprising a gravity drop-plate 49, hinged to the box or casing, similar to the form described in the application of William H. Baker and myself, Serial No. 83,497, filed November 25, 1901. Any other form of indicator may be used, the essential feature being that it shall give notice to the weaver that the filling has become exhausted. In the present example I attach an arm 50 to the shaft 32, said arm having at its outer end a contact-piece 51'. When said shaft is rocked, as before described, the arm 50 is brought into engagement with terminal plates 51, included in a circuit 52, thereby closing said circuit and causing the plate 49 to drop, as fully described in said application Serial No. 83,497. The particular indicator 46 shows the weaver that the filling has become exhausted, inasmuch as the circuit 52 is closed only when the shaft 32 is rocked through the operation of the controller-feeler. The other indicators 47 and 48 may be connected to stop-motion mechanisms—as, for example, a suitable warp stop-motion.

As shuttles vary in width, it is necessary or desirable that the relative distances between the two impinging-points of the controller may be adjustable or varied within certain limits. This adjustability may be secured in various ways—as, for example, as shown in Fig. 13, a screw-threaded shank 68, extending through a hole in the short arm of the trip-lever 13, is provided with a head 69, adapted to be impinged upon by the shuttle, and with two lock-nuts 70, which bear, respectively, on opposite faces of said arm. By adjusting the nuts 70 the head 69 may be moved in or out to adapt it to various conditions met with in practical work, so that the trip-lever will be impinged upon only when the filling in the shuttle is exhausted to exactly the desired extent.

In Fig. 14 I have shown the feeler-rod of Figs. 6 and 7 screw-threaded at its outer end 71 and a head 72 interiorly threaded and adjustable along said rod. The same result may be accomplished by the adjustment of the collar 62 along the feeler-rod 58 by means of a set-screw 73.

Other means for effecting the desired adjustment will readily suggest themselves. Not only is a delicate adjustment provided for by the means above described, but also a firm securing means to prevent shifting of the parts after they have once been adjusted.

Being the first, as I believe, to employ a compound mechanically-operating weft or filling exhaustion indicating device exterior of the shuttle with means common to both divisions for actuating loom-controlling mech-

anisms, I desire to claim the same broadly and do not limit myself to the precise details of construction shown. Being the first also to employ a purely mechanical feeler controlling the operation of an electrical annunciator device, I desire to claim the same broadly without reference to the specific means described for accomplishing the desired result.

While I have shown in this application the 10 feeler impinging upon the filling in the shuttle, it is to be understood that the feeler may impinge upon an interposed piece, as shown in Figs. 10 and 11 in my Patent No. 724,114, above referred to. It is also to be understood that while I have illustrated the invention 15 as applied to loom-stopping mechanism the invention is adapted to be used to control the time of operation of a weft-replenishing mechanism.

20 By "exhaustion" or "absence" or like term as referring to the weft or filling in the shuttle I mean such degree thereof as will permit the controller-feeler to operate while there is sufficient filling in either shuttle to prevent 25 an imperfection in the cloth being woven. By "bobbin" or "weft-holder" I mean any form of known weft-holder upon which weft or filling is placed for the purpose of feeding it to the web of the cloth.

30 By the phrase "weft or filling exhaustion indicating mechanism" is meant a device for controlling the time of operation of a weft-replenishing or loom-stopping mechanism.

What I claim, and desire to secure by Letters Patent, is—

35 1. In a double-shuttle loom, a compound mechanically-operating filling-exhaustion-indicating device having two independently-operable divisions, each division having two 40 members, means for impinging first on one of said members and means when exhaustion of the filling permits thereof of impinging first on the other member, loom-controlling mechanism, and means common to both divisions 45 of the indicating device for actuating, when required, said loom-controlling mechanism.

2. In a double-shuttle loom, a filling-exhaustion-indicating device having two independently-operable divisions which are impinged upon at each alternate beat up of the 50 lay, loom-controlling mechanism, and means operatively connected to both of said divisions and to said loom-controlling mechanism, whereby when the exhaustion of filling in 55 either shuttle permits thereof said connecting means may actuate said loom-controlling mechanism.

3. In a double-shuttle loom a filling-exhaustion-indicating device having two independently-operable divisions adapted to be impinged upon, loom-controlling mechanism, means intermediate and common to both said 60 divisions and said loom-controlling mechanism adapted to be actuated by either of said 65 divisions when the exhaustion of the filling permits thereof.

4. In a double-shuttle loom a weft or filling

exhaustion indicating device having two independently-operable divisions adapted to be impinged upon, loom-controlling mechanism, 70 a rock-shaft connected to said loom-controlling mechanism and means connecting said shaft to both of said divisions whereby said shaft may be actuated by either of said divisions when the exhaustion of the filling permits thereof. 75

5. A weft or filling exhaustion indicating mechanism for double-shuttle looms comprising a feeler device having two independently-operable divisions adapted to be impinged 80 upon by means in the shuttles, loom-controlling mechanism and a rock-shaft connected thereto, a lever device operatively connected to said rock-shaft and to both of said divisions whereby said shaft may be actuated 85 when the filling in either shuttle has been exhausted to a predetermined extent.

6. A weft or filling exhaustion indicating mechanism for double-shuttle looms comprising a feeler device having two independently-operable divisions adapted to be impinged upon by means in the shuttles, loom-controlling mechanism comprising a rock-shaft, and a bell-crank lever connected to said shaft and in operative engagement with both of said 95 divisions whereby said shaft may be rocked when the filling in either shuttle has been exhausted to a predetermined extent.

7. In a loom the combination with stopping mechanism, of a mechanical controller-feeler 100 for setting in operation said stopping mechanism, and electromechanical means to announce that the filling has been exhausted.

8. In a loom the combination with stopping mechanism, of a mechanical controller-feeler 105 for setting in operation said stopping mechanism, an electric circuit an indicating device included in said circuit, and means actuated by said controller-feeler to change said circuit when the filling has been exhausted 110 to a predetermined extent.

9. In a loom the combination with stopping mechanism, of a mechanical controller-feeler, a rock-shaft actuated by said controller-feeler to set in operation said loom-stopping mechanism, an electric circuit, an indicating device included in said circuit, and an arm on said shaft adapted to change said circuit when the filling has been exhausted to a predetermined extent. 115

10. In a double-shuttle loom, a loom-controlling feeler device having two independently-operable divisions, said divisions each consisting of a yieldingly-mounted feeler bearing a lever-like tripping device, of means 125 for operating said tripping device in either or both of said divisions when said feelers pass a certain predetermined distance into their respective shuttles, and mechanism common to said tripping devices and adapted to 130 be operated thereby.

11. In a double-shuttle loom, a filling-exhaustion-indicating mechanism having two independently-operable divisions each com-

prising a yielding feeler adapted to be impinged upon by means in the respective shuttles, a normally quiescent lever device carried by said feelers, said lever device having 5 a heel or part which is held out of the path of the shuttle by the feeler during the normal operation of the loom, and mechanism actuated by either of said levers when its heel is permitted to be impinged upon by its 10 respective shuttle through the exhaustion of the filling therein to a predetermined extent.

12. In a double-shuttle loom, filling-exhaustion-indicating devices and means to visually announce when the filling in either or both 15 of the shuttles is substantially exhausted.

13. In a double-shuttle loom, filling-exhaustion-indicating devices, and means common to both shuttles including an annunciator for visually indicating the substantial exhaustion 20 of the filling in either or both of the shuttles.

14. A mechanical weft or filling exhaustion indicating mechanism for a loom, comprising a yielding feeler adapted to be impinged upon 25 by means in the shuttle, a normally quiescent lever-like tripping device carried by said feeler, said lever device having a heel or part which is held out of the path of the shuttle during the normal operation of the loom, 30 mechanism actuated by said lever when said heel is permitted to be impinged upon by the shuttle through the exhaustion of the filling therein to a predetermined extent, said feeler normally protruding beyond the impinging 35 face of said trip-lever, and means to adjust the degree of projection of the said feeler and the said tripper relatively to each other.

15. A weft or filling exhaustion indicating mechanism for looms, comprising a feeler 40 adapted to be impinged upon by means in the shuttle, a lever device operatively con-

nected therewith and adapted to remain quiescent as long as a predetermined amount of filling remains in the shuttle, mechanism actuated by the movement of said lever device 45 when the filling in the shuttle has been exhausted to a predetermined extent, and adjustable means adapted to vary the degree of projection of the said feeler and said lever device relatively to each other. 50

16. In a double-shuttle loom, a compound mechanically-operating filling-exhaustion-indicating device having two independently-operable divisions, each division having two members, means for impinging first on one 55 of said members and means, when exhaustion of the filling permits thereof, for impinging first on the other member, loom-controlling mechanism, means common to both divisions of the indicating device, for actuating, when 60 required, said loom-controlling mechanism, one of said members protruding at its impinging face beyond the impinging face of the other, and adjustable means adapted to vary the normal extent of said protrusion. 65

17. In a double-shuttle loom, a controlling filling-exhaustion-indicating device having two independently-operable divisions, means for impinging upon said divisions, loom-controlling mechanism, and means operatively 70 connected to both of said divisions and to said loom-controlling mechanism, said divisions being held inoperative by the presence and made operative by the substantial exhaustion or absence of filling in the shuttles. 75

In testimony whereof I have signed my name to this specification in the presence of two subscribing witnesses.

FREDERIC E. KIP.
